UNITED STATES PATENT OFFICE.

CLAUD J. CLEFTON, OF OWATONNA, MINNESOTA, ASSIGNOR TO THE CLEFTON COMPANY, OF OWATONNA, MINNESOTA, A CORPORATION OF MINNESOTA.

GAS-GENERATOR.

1,112,597.

Specification of Letters Patent.

Patented Oct. 6, 1914.

Application filed July 27, 1912. Serial No. 711,854.

To all whom it may concern:

Be it known that I, CLAUD J. CLEFTON of Owatonna, Steele county, Minnesota, have invented certain new and useful Improvements in Gas-Generators, of which the following is a specification.

The object of my invention is to provide an improved form of auxiliary carbide can which is easily accessible and can be filled or emptied of its charge without opening the main carbide can of the generator.

A further object is to provide a generator of simple, durable construction and one which can be easily filled and operated.

The invention consists generally in various constructions and combinations, all as hereinafter described and particularly pointed out in the claims.

In the accompanying drawings forming part of this specification, Figure 1 is a vertical sectional view of an acetylene generator embodying my invention, Fig. 2 is a detail sectional view of the upper portion of the generator, Fig. 3 is a plan view of the carbide can, Fig. 4 is a vertical sectional view through the auxiliary or supplemental carbide can, Fig. 5 is a detail view of the valve which controls the discharge of the carbide from the can into the water in the tank beneath. Fig. 6 is a detail sectional view of the gas purifying device.

In the drawing, 2 represents a tank adapted to contain a supply of water and having an open top provided with a cover 3 and supporting a ring 4 upon which a second cover 5 is arranged. A chamber 5' is formed between the covers, serving as a dead air space, and when the generator is buried in the ground, only the upper cover will be exposed and the carbide and the gas bell contained within the tank will be protected to a very large degree from exposure and heat and cold by the double arrangement of the covers and the dead air space between them.

Within the tank 2, below the level of the water, is a ring 6, preferably of channel bar iron, supporting a series of legs 7' which are inclined inwardly and upwardly and are held in their proper relative position by means of a circular band 7 provided at the lower ends of the legs and by rings 8 and 9. A band 10 is provided below the rings 6 and cooperates with the band 7 to direct the ascending gas toward the middle of the tank

and prevent it from passing up through the water between the tank and the gas bell.

11 represents the gas bell, having a strengthening ring 12 at its lower end that is adapted to rest on seats 13 mounted on the legs 7', near the ring 6. The lower end of this bell is open to allow the gas to ascend therein as the carbide falls into the water in the tank, and the top of the bell has a cover 14 on which straps 15 are mounted which are adapted to interlock with lugs 16 secured to an annular flange 17 at the top of the gas bell 11. The flange 17 has a depending portion 18 which cooperates with a cylinder 19 to form an annular chamber 20 that is adapted to contain a quantity of oil or similar sealing material and receive the depending flange 21 on the cover 14. This seal between the cover and the cylinder enclosing the carbide can not only prevents the escape of gas around the cover but also allows the removal of the cover and access to the carbide can at any time without removing or disturbing the gas bell. This cylinder 19 is open at each end and is adapted to receive a carbide can 22 which has a hopper shaped lower end terminating in discharge openings 23.

A band 24 is secured to the legs 7' and encloses the upper portion of the carbide can 22. In its normal position the can 22 rests upon the ring 9. The carbide can has a tube 25 centrally mounted therein and adapted to receive a valve stem 26 on which is mounted a disk 27 having holes 28 therein which register with the discharge openings 23 in the bottom of the carbide can. This disk is capable of rotation so that the holes therein will be in or out of register with the holes in the basket, according to the position of the rotating valve. At the upper end of the stem 26 is a crank 30 having a recess 31 therein and adapted to receive a pin 32 on a lever 33 which is pivoted at 34 within a housing 35 mounted on the closed top of the carbide can 22. A weight 36 is provided at one end of the lever 33 and an arm 37 at the opposite end, said arm projecting upwardly above the top of the housing normally and having an anti-friction bearing. The contact of the gas bell with the arm 37 will rock the lever 33, swing the crank 30 and rotate the disk valve sufficiently to cause the holes 28 to register with those in the bottom

of the carbid can. When this has been done the carbid will flow out of the can and through a deflecting ring 38 which has a central opening and is mounted within a 5 pipe 39 which incloses the openings in the lower end of the gas can and is secured to the walls thereof. Evidently when the stem 26 is oscillated the valve will be turned also until its ports register with those in the bot- 10 tom of the can, when the carbid will flow freely therethrough and falling upon the ring 38 will be deflected toward the center so that the carbid will fall into the water at the center of the tank or at a point very 15 close to the center. The ring 38 also acts as a baffle to prevent the water which might boil or splash up when the carbid strikes the water from wetting the disk 27. The part 38 has pins 40 thereon which are adapt- 20 ed to enter bayonet slots 41 provided in the ring 39 for convenience in assembling the parts or separating them. When the gas bell descends, as the gas supply decreases, it will finally contact with the arm 37, tilting 25 the lever 33 and oscillating the valve disk to expose the openings in the bottom of the carbid can and allow the carbid to flow by gravity down through the openings in the bottom thereof and into the water in the tank.

It sometimes happens that the charge of carbid in the can becomes exhausted during the evening or at some time when it may be extremely inconvenient or annoying to 35 recharge the can. I therefore provide an auxiliary or supplemental can adapted to contain a comparatively small amount of carbid and by means of which the person in charge of the generator can easily and 40 quickly deliver a sufficient quantity of carbid into the water in the tank to run the generator for several hours. This auxiliary can consists of a receptacle 41 having a hopper bottom provided with a discharge 45 opening 42 normally closed by a valve 43 having a stem 44 that is connected to a lever 45 pivoted at 46 on the top of the receptacle. The lug 47 projects beyond the edge of this lever into the path of a vertically 50 sliding rod 48 which has a lower loop portion depending into the tank and a lifting arm 49 which extends up between the tank and the wall of the gas bell to a point where it can be conveniently reached upon remov- 55 ing the covers 3 and 5. It is only necessary, therefore, for the person in charge of the generator to raise the covers, pull up the rod 49 and open the valve 43 to allow a sufficient quantity of the carbid to drop down 60 into the can and from thence into the tank to run the generator for several hours.

On one side of the tank is a pipe 50 through which the residue of the carbid may be pumped and if preferred, the tank 65 may be supplied with water through this

pipe. A pipe 51 is provided on the other side of the tank communicating at its upper end with the service pipe 52 and its lower end communicates with a pipe 53 within the generating tank. A purifying device is 70 mounted on the pipe 53 and comprises a cup 54 adapted to contain a supply of water and a cylinder 55 having its lower end depending into the water in the cup 54 and forming a water seal therewith and provided with a cover 56 having a seal 57. The pipe 53 is open at its upper end and within the cylinder and inclosing pipe 53 is a quantity of purifying material 58, through 75 which the gas is obliged to flow before it reaches the open upper end of the pipe 53. A screen 59 is preferably provided in the purifier and a series of deflectors 60 are mounted therein between said screen and the cup 54, said deflectors compelling the 80 gas to follow a tortuous passage through the lower portion of the purifier before reaching the screen. The depth of the seal in the cup 54 may be varied according to the pressure desired in the tank. Generally, 85 however, the seal as shown in Fig. 6 will be sufficient for all purposes. In the operation of the generator, the gas must pass through and wash itself in the water held in the cup 54 before it can enter the cylinder 55. 90

A valve 61 is provided in the service pipe 52 and has an operating handle 62 extending above the surface of the ground and inclosed in a suitable case or housing 63. This valve is adapted to open communication between the generator and the service pipe 100 and has an exhaust opening through which the gas in the system or in the tank may be discharged.

The weighted lever having the crank connection with the valve stem shown in Fig. 2 of the drawing, I do not claim in this application, but have included it in a pending case filed December 30, 1912, Serial No. 739,276, renewal Serial No. 811,280. 105

I claim as my invention:—

1. An acetylene generator comprising a tank adapted to contain a supply of water, a carbid can supported within said tank and means for controlling the discharge of the carbid from said can, an auxiliary carbid can mounted in the top of said first named can and partly within it and having a discharge opening through which the carbid from said auxiliary can is discharged into 115 said first named can, a valve for closing the discharge opening in said auxiliary can, a stem for said valve projecting through the top of said auxiliary can, a cover for said tank between which and said first named carbid can the upper portion of said auxiliary can projects to allow access to said auxiliary valve stem when said cover is removed. 120

2. An acetylene generator comprising a 130

- 1 tank adapted to contain a supply of water, a carbid can having discharge openings and means for controlling the discharge of the carbid from said can, an auxiliary carbid can having a discharge opening and a valve therefor, and a cover, said auxiliary can being positioned partly within said carbid can, whereby filling of said auxiliary can is permitted without opening said carbid can.
- 10 3. An acetylene generator comprising a tank adapted to contain a supply of water, a carbid can having a discharge opening and means for controlling the discharge of carbid from said can, an auxiliary carbid can mounted in the top of said first named can and partly within it and having a discharge opening within said first named can and a filling opening on the outside thereof, and a cover for said auxiliary carbid can.
- 15 4. An acetylene generator comprising a tank adapted to contain a supply of water, a carbid can mounted therein and having a discharge port, means for regulating the flow of carbid from said can, an auxiliary carbid can arranged to discharge its contents into said first named can, said auxiliary can being positioned partly within said carbid can, whereby filling of said auxiliary can is permitted without opening said carbid can, a valve normally closing the flow of carbid from said auxiliary can, and a rod within control of the operator for actuating said auxiliary can valve to release the carbid therein.
- 20 5. An acetylene generator comprising a tank adapted to contain a supply of water, a carbid can supported within said tank and having a discharge opening and means for controlling the discharge of the carbid from said can, an auxiliary carbid can mounted in the top of said first named can and projecting above the same and having a discharge opening within said first named carbid can, a valve for said discharge opening, said auxiliary can being adapted to contain a night charge of carbid and having a suitable opening and a cover therefor, and means for operating the valve of said auxiliary carbid can through the top thereof, said auxiliary can being located partly within said carbid can and accessible for filling purposes without opening said first named carbid can.
- 25 In witness whereof, I have hereunto set my hand this 18th day of July 1912.
- 30 CLAUD J. CLEFTON.
